[57] ABSTRACT

An atomic beam resonator having a source for producing the beam, a first and second state selector separated by an interaction zone, means for generating an oscillating field in the interaction zone, and a detector. The second state selector is a dipole magnet having pole pieces of trapezoidal shaped in such a way that, in a plane perpendicular to the beam axis, the field is described by a set of confocal conics, the equipotentials being hyperbolae and the field lines ellipses.

FIG 5

ATOMIC BEAM RESONATOR HAVING A CONFOCAL CONICS FIELD GEOMETRY IN THE SECOND STATE SELECTOR

The purpose of this invention is to obtain an improved efficiency together with a simple design of the second state selector of an atomic beam resonator, in particular a cesium beam tube.

Cesium beam tubes are known as being absolute frequency standards of high accuracy and are used as frequency determining elements in atomic frequency and time standards or clocks.

The principle of operation of atomic beam resonators is well known and shall not be described here in detail. U.S. Pat. No. 3,591,800 contains such a description and also discusses means to obtain an improved efficiency of the state selectors. Referring to this earlier work, the present invention discloses an apparatus which provides a similar result as obtained with the prior apparatus, but with a state selector magnet having a much simpler geometry of the pole pieces. This leads to a reduction in cost of manufacturing.

BRIEF DESCRIPTION OF THE DRAWINGS

The accompanying drawings illustrate the prior art and various embodiments of this invention. In such drawings:

FIG. 1 is a cross-section of the second state selector described in the earlier patent (U.S. Pat. No. 3,591,800);

FIG. 2 shows a cross-section of a second state selector embodying this invention;

FIG. 3 shows a cross-section of another embodiment of this invention;

FIG. 4 shows a section along the beam axis of the state-selector according to FIG. 3.

FIG. 5 shows a schematic view of an atomic beam resonator comprising the second state selector 16 embodying this invention, all other parts being of prior art design.

The physical arrangement of the main components of an atomic beam resonator is shown schematically in FIG. 5. The atomic beam is formed by a source 13 which, in the case of a cesium beam resonator, consists of an oven containing liquid cesium metal, heated to a temperature producing sufficient vapor pressure and having an aperture with collimating channels to form the beam. The atomic beam passes through a first state selector 14 magnet which in this example may be a quadrupole or hexapole magnet whose symmetry axis coincides with the axis of the beam.

It is well known that this kind of magnet has the property of focusing atoms which are in a higher hyperfine energy level by deflecting these atoms 22 towards the axis, whereas the atoms 23 of a lower hyperfine energy level are deflected away from the axis and eliminated. The atoms 22 remaining in the beam pass through an interaction zone 15 where they are exposed to an oscillating magnetic microwave field produced by means of an external generator 21. If the power level and the frequency of the microwave generator are correctly adjusted, the atoms undergo transitions to the lower hyperfine level. The rate of transition is extremely sensitive to the frequency of the microwave field and it attains a sharp maximum at the frequency corresponding to the hyperfine energy level separation.

The purpose of the second state selector 16 is to collect those atoms 24 which have made the transition to the lower energy level on to a detecting device 18 and to eliminate the atoms 25 which have remained in the higher level. In the case of cesium atoms, the detecting device 18 consists of a hot wire or ribbon which ionizes the incident atoms, the latter being collected on an electrode and producing a current proportional to the rate of transitions. A beam stop 17 prevents fast undeflected atoms from hitting the detector and causing an unwanted background current.

The second state selector 16, which in FIG. 5 is shown only very schematically, is the subject of the present invention and is therefore discussed in more detail in the following paragraphs.

The atomic beam apparatus is enclosed in an evacuated envelope 19. The output current is fed into an automatic frequency control system 20 which acts on the microwave generator 21 to control the frequency in such a way as to keep this frequency at the value producing the maximum transition rate and hence the maximum output current. By this means, the frequency of the generator 21 is stabilized by means of the atomic beam resonator and the whole system can be used as an atomic frequency standard or clock, all as described in my earlier U.S. Pat. No. 3,591,800.

The second state selector described in the earlier patent (U.S. Pat. No. 3,591,800) and shown in FIG. 1 herein comprises a field concentrating rod 1 which is placed in the center of the gap formed by the concave pole pieces 2 and 3. The axis of the beam is perpendicular to the plane of the drawing. The atoms pass through the gaps between 2, 1 and 1, 3 respectively. The force acting on the magnetic moment of the atoms causes a deflection of those atoms which are in the desired quantum state (i.e., those having the transition to the lower energy level) towards the detector element 18 of FIG. 5 placed along the axis of the beam and located at some distance behind the central pole piece 1. The force acting on the atom is proportional to the product of its magnetic moment and the gradient of the magnetic field. Thus the direction of the force does not depend on the direction of the field itself but on the direction of its gradient. In our case, the magnetic moment of the atoms in the desired state is positive and the force acts in direction of increasing field strength.

This invention discloses a different and new design of the second state selector which provides a similar result and avoids the disadvantages of the prior art device shown in FIG. 1. These disadvantages are the following:

The central pole piece 1 obstructs a considerable fraction of the beam cross section. Almost half of the beam intensity is lost.

The means of supporting and aligning the central pole piece 1 are complicated and thus relatively expensive.

The manufacturing of the pole pieces 1, 2 and 3 requires delicate and costly milling and turning operations in order to obtain the shapes within the required close tolerances.

These disadvantages are due to the presence of the central pole piece. The same problems also exist in the state selectors of the multiple beam resonators described in recent publications (R. Hyatt et al. "Performance of Newly Developed Cesium Beam Tubes

and Standards," Proceedings of the 25th Annual Symposium on Frequency Control, 26 - 28 April, 1971, U.S. Army Electronics Command, Ft. Monmouth, New Jersey) and in U.S. Pat. No. 3,675,149 (Cutter et al.). In practice, these disadvantages have been accepted because the obtained efficiency was still very good compared to that of earlier designs.

The present invention provides a similar high efficiency but avoids the drawbacks mentioned above.

FIG. 2 illustrates the principle of this invention. The pole pieces 4 and 5, made of a ferromagnetic alloy having a high permeability at high fields (e.g. Iron - Cobalt - Vanadium alloys) constitute equipotential surfaces which define the field in the region of the gap. The length of this assembly, in the direction of the z axis perpendicular to the plane of the drawing, is assumed to be sufficiently large compared to the gap width so that fringe effects can be neglected. The pole pieces 4 and 5 comprise flat surfaces only which are easy to machine. They constitute an approximation to a pair of surfaces having hyperbolic cross section. The field in the gap is thus defined by sets of confocal conics. The cross sections of the equipotential surfaces are hyperbolae and the field lines are ellipses. The detector filament is placed in the y-z plane at some distance beyond the magnet shown in the figure. Outside the y-z plane the field gradient has a component which is directed towards this plane. The atoms to be detected are deflected in the direction of the gradient and therefore in the direction of the y-z plane containing the detector element. Atoms in other states having a negative magnetic moment are deflected in the opposite direction away from the detector element and are not detected.

In order to avoid detection of weakly deflected fast moving atoms, a beam stop 17 (see FIG. 5) may be placed in front of the magnet and in the y-z plane. However, the width (in the x-direction) of such a stop can be just slightly larger than that of the detector filament.

The atoms hitting the beam stop 17 are lost, but this loss is negligible compared to the loss due to the wide central pole piece shown in FIG. 1.

Another embodiment of this invention is shown in FIG. 3. Here, the plane of symmetry containing the x and z axes of FIG. 2 is replaced by a flat pole piece 6. According to the mirror effect known from potential field theory, the field in the remaining gap is the same as in the upper half of FIG. 2, the other pole piece 7 being identical to 4 and 5.

Outside of the x-z plane the gradient is not everywhere parallel to this plane but may be directed towards the tip of the pole piece. This causes some defocusing in the y-direction and the loss of atoms hitting the pole piece. The useful deflection angles being very small, this loss is not very important. It can be made negligible by the modification shown in FIG. 4 which represents a section along the beam axis, i.e. in the y-z plane, of the state selector shown in FIG. 3. Here the surface 8 of the pole tip 9 is not parallel to the plane surface of the flat pole piece 10. The gap width increases slightly in the direction of the atomic beam 11 towards the detector filament 12. Thus the number of

atoms hitting the pole piece is reduced.

All pole pieces shown in the FIGS. 2, 3 and 4 comprise only flat surfaces of simple geometry. They are easier to manufacture and therefore less expensive than the curved pole pieces used in earlier designs. One could be tempted to see in these designs a return to the old types of state selectors designed by Stern and Gerlach and Rabi, which are described in N. F. Ramsey's book "Molecular Beams" (Oxford 1956, pp 394-396). However, in this invention the field is well described by sets of confocal conics, and this is not the case in the above mentioned state-selectors which are only of historical interest.

The present invention may be embodied in other specific forms without departing from the spirit or essential characteristics thereof. The presently disclosed embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein.

I claim:

- 25 1. In an atomic beam resonator comprising a source means for producing and projecting a beam of atoms over an elongated predetermined beam path, first state selector means adjacent to said source for deflecting atoms in said beam, a second state selector means downstream of said first state selector means for deflecting atoms in said beam, said state selector means being separated in order to provide an interaction zone, means for generating an oscillating magnetic field in said interaction zone, and a beam detector device downstream of said second state selector means for detecting only atoms in said beam having undergone transitions between two magnetic hyperfine energy levels by having interacted with said oscillating magnetic field, the improvement wherein said second state selector means comprises a two pole piece magnetic assembly for producing a magnetic field through which said beam path extends, at least one of said magnetic pole pieces being trapezoidal in cross section in a plane perpendicular to the axis of the beam path and having flat external surfaces for producing a magnetic field described in said plane by sets of confocal conics, the equipotentials of said field being hyperbolic and the field lines elliptic.
- 30 2. An atomic beam resonator as set forth in claim 1 wherein said magnet pieces have flat surfaces approximating an equipotential surface of hyperbolic cross section.
- 35 3. An atomic beam resonator as set forth in claim 1 wherein one of the pole pieces of said magnet assembly has flat surfaces approximating an equipotential surface of hyperbolic cross section and the other pole has a plane surface.
- 40 4. An atomic beam resonator as set forth in claim 1 wherein the width of the gap between said magnet pole pieces increases in the direction towards said detector device.
